(57) **CLAIM**

The ornamental design for a face plate for plumbing fixture, as shown and described.

DESCRIPTION

FIG. 1 is a right, top, front perspective view of a face plate for plumbing fixture embodying my new design; and, FIG. 2 is a front elevational view thereof.

The broken line representation of a mounting environment in FIG. 1 is for the purpose of illustration only and forms no part of the claimed design.

In a preferred embodiment, the nature of this product is as a flow distributor primarily useful for enabling a water spray from a plumbing fixture.
